Primary Examiner — April Rivas(74) *Attorney, Agent, or Firm* — Heedong Chae; Lucem, PC(57) **CLAIM**

The ornamental design for a case for a charging case, as shown and described.

DESCRIPTION

FIG. 1 is a front perspective view of a case for charging case showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded front perspective view of the case separated from the charging case.

The broken lines illustrate portions of the case for charging case. The broken line charging case in FIG. 9 illustrates environment. None of the broken lines form part of the claimed design.

1 Claim, 9 Drawing Sheets(56)
